DESIGN FOR A KEEPER PLATE FOR SUIT-CASES AND THE LIKE

Robert S. Wagner, Milwaukee, Wis., assignor to
E. R. Wagner Manufacturing Company, Milwaukee, Wis., a corporation of Wisconsin

Application August 23, 1943, Serial No. 110,981

Term of patent 14 years

To all whom it may concern:

Be it known that I, Robert S. Wagner, a citizen of the United States, residing at Milwaukee, in the county of Milwaukee and State of Wisconsin, have invented a new, original, and ornamental Design for a Keeper Plate for Suitcases and the like, of which the following is a specification, reference being had to the accompanying drawing, forming a part thereof, and in which:

Figure 1 is a view in top plan of a keeper plate for suitcases and the like, showing my new design.

I claim:

The ornamental design for a keeper plate for suitcases and the like, as shown.

ROBERT S. WAGNER.
